UNITED STATES PATENT OFFICE

KNUD MURCK, OF FOREST HILLS, NEW YORK, ASSIGNOR TO CHARLES BRUNING COMPANY INC., A CORPORATION OF NEW YORK

PAPER-DEVELOPING ATTACHMENT

Application filed January 25, 1929. Serial No. 334,898.

The object of this invention is to provide an apparatus for developing sensitized papers of the kind which do not require washing and drying, but which are developed by moistening with a special chemical solution, and from which positive copies are obtained by direct printing.

The invention relates to the art of copying originals in the manner of blue printing, but whereas the developing of blue print papers requires elaborate machinery for quantity production necessitated by the demands of modern industry, the sensitized papers referred to may be developed by very simple apparatus and require only a slight moistening of the developing solution after which they are ready for use.

One of the objects of this invention is to provide an apparatus for developing such sensitized papers so arranged and constructed that the apparatus may be incorporated as a unit into a modern standard continuous blue printing machine whereby the industry may take advantage of the improved sensitized papers and processes without the disadvantage of having to discard costly machinery.

Accordingly the invention is embodied in an apparatus which may be quickly attached to a continuous blue printing machine and whereby the washing and drying blue print machine units may be dispensed with. The invention therefore is of great practical utility, because not only does it permit the continued use of existing machinery, but it effects the discontinuance of an expensive continuously flowing water supply and of continuously operated heating units for drying purposes. In the accompanying drawings

Figure 1 is a diagrammatic illustration of a standard continuous blue printing machine equipped with an attachment embodying the invention and in which the washing and drying elements are omitted.

Figure 2 is a perspective view of the attachment.

Figure 3 is a detail sectional view of the developing roller and its trough.

Figure 1 illustrates a typical continuous blue printing machine in which the original and the blue print paper is fed on a work-

ing table 5 onto an endless canvas belt 6 which runs over rollers 7, 8 and 9 and presses the original and the blue print paper against a semi-circular transparent platen 10. In the focal center of the platen there is a suitable lamp 11.

The original is exposed during its passage over the platen and the blue print is made. The original is then removed but the blue print paper, which comes from a roll, is threaded through the machine and up over a roller 12 and passes continually through the machine, originals being inserted one after the other.

In its passage through the machine and up to the roller 12, and preferably immediately before reaching the latter, the blue print paper is washed, i. e. developed, by means of a constant flow of water directed against the paper. After it passes over the roller 12, the paper is led past a battery of steam pipes and dried. The prints are then finished.

The canvas belt 6 is operated from a motor 14 by means of gears 15 and 16, and bevel gears 17 and 18. The latter drives an upright shaft 19 from which the canvas roller 9 is driven by bevel gears 20 and 21.

The roller 12 is driven by sprockets and gears which by means of chains 22, 23 and 24 transmit motion to the roller as shown and in a manner known in the art. 25 indicates a part of the general framework of the machine.

The foregoing describes the well known process of operating a continuous blue print machine.

According to this invention the blue printing machine is utilized for continuous printing purposes, but the washing and drying units are either removed or rendered inoperative and therefore not shown, and into the blue printing machine structure is fitted an attachment for developing the sensitized paper by exposure to a special chemical solution.

Referring now to Figures 2 and 3 the attachment consists of two side frames each of which comprises a horizontal support 26, an upwardly inclined support 27 and an inclined leg brace 28. The supports and the

brace are joined at a common point at 29. The inner ends of these members are mounted on the uprights 25 of the blue printing machine by bolts 30. The uprights are at the 5 outsides of the machine and the several rollers, etc. are mounted therebetween.

On the horizontal supports 26 there are mounted two bearings 31, 31 in which the developing roller 32 is journaled. Between 10 the bearings and below the developing roller there is mounted a trough 33 for containing the developing solution. On each member 26 there is further supported a depending bearing 35 and an idler roller 36 is journaled in the bearings 35.

15 Each upwardly inclined member 27 supports a bearing 37 and another idler roller 38 is mounted in these bearings. The solution for developing the paper may be poured 20 into the trough in any convenient manner. However, it has been found most practical to have the solution in a container 4 on a shelf 41 conveniently secured to the one side frame. A valve controlled hose 42 leads from the 25 container to the trough 33.

The shaft 43 of the developer roller 32 is extended beyond the one bearing 31 and on it is mounted a sprocket 44, Figure 1, which is driven by a chain 45 from another sprocket 46 conveniently driven by gearing 47 inserted in the driving mechanisms 23 of the machine so that the developer roller is driven faster than the speed at which the paper passes through the machine.

35 The sensitized paper 50, fed from a roll, not shown, and the original 51 are together led into the machine over the working table 5 the same as with the blue print paper. After exposure the original is removed, see 40 arrow 52, and the print paper continues through the machine over the canvas roller 9. A heavy rod or roller 53 rests on the paper to keep it taut, and the paper then continues its travel over an idler 54, which is part of 45 the blue printing machine and thence to the attachment rollers.

Here the paper passes under the roller 36, up over the developer roller 44, thence under the roller 38 to the roller 12 and out. The 50 attachment rollers 36, 32 and 38 are spaced in a predetermined fixed relation to insure that the paper 50 makes just sufficient contact with the developer roller to bring out the print, yet not become too moist. It has been found 55 that if a developer roller of about two inches diameter is used, the paper is developed by contacting with the roller of a space of about one inch. At the same time, it is sufficient if only enough solution is kept in the trough to 60 keep the roller 32 moist without causing dripping.

In actual practise it has been found that the development takes place so rapidly that the paper is dry after passing over the roller 65 12. The machine may therefore be operated

continuously and prints having black lines on white ground turned out by merely passing through the machine and without requiring washing or drying.

With very slight changes, therefore, existing continuous blue printing machines may 70 be used for printing and developing the new paper.

It will be observed that the attachment is in knock down form, easy for shipment and installation by means of bolts and screws. 75 The prints are much superior to blue prints because of the black lines on white background which is easier to read and permits of coloring, writing and easy changes.

I claim:

A sensitized paper developing mechanism of the character described comprising horizontal supporting members, a trough for containing a developing solution supported thereon, a developing roller rotatably mounted between said members and partly within the trough, inclined supporting members disposed on opposite sides of said horizontal members, guiding rollers mounted on said inclined supporting members for guiding the paper into operative relation with said developer roller, all of the aforesaid elements being assembled to form a self contained unit adapted to be attached to a sensitized paper printing machine and means for operating said unit.
